UNITED STATES PATENT OFFICE.

REINOLD BERRENBERG, OF BOSTON, MASSACHUSETTS.

ROTARY PUMP.

No. 878,600.

Specification of Letters Patent.

Patented Feb. 11, 1908.

Application filed March 27, 1907. Serial No. 364,914.

To all whom it may concern:

Be it known that I, REINOLD BERRENBERG, of Boston, in the county of Suffolk and State of Massachusetts, have invented a new and useful Improvement in Rotary Pumps, of which the following, taken in connection with the accompanying drawings, is a specification.

My invention relates to the peculiar internal construction of the pump, by means of which I am enabled to dispense with sliding pistons, and thereby produce a pump that has but few parts, and one that is very solid and durable. The construction and 10 operation of my invention is illustrated in the accompanying drawings, in which

Figure 1 is a side elevation of my pump; Fig. 2 is a view showing parts in horizontal section, taken on line 2—2 of Fig. 7, also 20 showing a part in full, of the rotating piston, and one form of the valve. Fig. 3 is a horizontal section of the body part of the pump, showing the base, shaft and fly-wheel. Fig. 4 is a vertical cross section, taken on line 4—4 of Fig. 3, showing the interior of 25 the casing, omitting the piston, and showing the end of the valve in full. Fig. 5 is a view in elevation, showing the piston and the main shaft. Fig. 6 is a plain view of the 30 sliding valve. Fig. 7 is a view of the interior of the pump, showing the piston all in elevation.

The peculiar and dominant feature of my pump is the rotating piston, shown in full in 35 Fig. 5; this, it will be noticed, has a cylindrical surface and end surfaces which consist of annular warped surfaces and disk surfaces; that is, referring to Figs. 4 & 5, the surface P⁴, is cylindrical, the annular end surfaces P², P², are warped, and the end surfaces P³, P³, are circular disks, as shown. The 40 parts of the rotating piston P that I have referred to as disks, are the ends of the central part P¹ (see Fig. 3) of the piston, and are closely fitted to the interior faces of the 45 bosses C¹ and E¹ that are made on the ends C and E of the casing. The rotating piston P is keyed or otherwise made fast to the main shaft D, upon which is mounted the 50 fly wheel D¹.

The casing of my pump consists of a cylindrical part B mounted upon standards A¹ A¹, which form a part of the base A.

The valve V is a metal plate adapted to slide longitudinally or parallel with the axis; 55 it is guided in ways K¹ K¹, Fig. 4, and by grooves C³ made in the bosses C¹ and E¹ of the end pieces C and E. This valve V is recessed as shown in Fig. 6 and is adapted to fit the rotating piston P and is made to slide 60 longitudinally by the rotation of the piston P. This pump is of the duplex order, having a piston chamber upon each side of the piston, and having two inlet ports I and I¹ and two outlet ports O and O¹, the inlet 65 ports being below the valve V, and the outlet ports above the same, so that as the piston rotates the piston chambers of the inlet ports I and I¹ is always increasing in capacity with slight interruption, and the piston chambers or pockets in connection with the outlet ports O and O¹ are always growing smaller with the same slight interruption, therefore when the piston rotates there is practically a constant stream of liquid flowing 70 to and from the pump. 75

The valve chamber, shown in Figs. 1, and 2, has end pieces, K, K, and an outside plate L. The ways, in which the valve slides, are indicated by K¹ K¹ Fig. 4. 80

The valve V, as shown in Fig. 2, is slightly different from that shown in Figs. 4 and 7, viz., it is slightly narrower, and is provided with anti-friction rolls R R R, otherwise it is exactly like the valve V shown in the other 85 drawings.

Claim

A rotary pump comprising a casing having suitable inlet and outlet ports and having on the inner ends of the casing inwardly 90 projecting bosses, the said bosses being grooved, whereby ways or guides are provided for the valve to slide in; a rotating piston, the central part of which is disk shaped and constructed to fit the faces of the 95 said bosses and thereby form a comparatively water-tight joint, the outer part of said piston being an annular sinuous ring, the peripheral surface of which fits the inner cylindrical surface of the casing and a sliding 100

valve constructed to be operated by said piston and to co-act with the same to force the contents of the piston chambers into the outlet ports, substantially as and for the 5 purpose set forth.

In testimony whereof, I have signed my name to this specification in the presence of

two subscribing witnesses, on this 18th day of March, A. D. 1906.

REINOLD BERRENBERG.
